JOHN J. CROWE, OF WESTFIELD, NEW JERSEY, ASSIGNOR TO AIR REDUCTION COMPANY, INCORPORATED, OF NEW YORK, N. Y., A CORPORATION OF NEW YORK

FLAME REGULATING COCK

Application filed December 20, 1929. Serial No. 415,429.

The invention relates to oxyacetylene and like torches for welding and cutting, and the object is to secure a simple and effective means for flame adjustment.

In the usual practice separate needle valves are placed in the oxygen and fuel gas passages of the torch, so that by independent manipulation of these valves the flame can be adjusted to a neutral composition, or to a somewhat oxidizing or somewhat carbonizing condition if either should be desired. Two-hole cocks have also been employed for turning on and off both gases simultaneously without disturbing needle valve adjustment.

The subject of the present invention is a torch provided with a single cock for controlling both gases, this cock being capable of adjusting the flame in respect to neutrality by a slight turning movement of the cock in one direction or the other, and being further capable of changing the flame from a large to a small flame or vice-versa by a greater turning movement.

In the accompanying drawings forming a part hereof:

Fig. 1 is a sectional view of a double flame adjustment cock in accordance with the invention;

Fig. 2 is a similar view showing the plug turned through 180° to secure a small flame; and

Fig. 3 is a schematic plan view.

The combination constituting the invention enables the flame to be changed from a large flame to a small flame, and vice-versa, by turning the plug 10 by its wheel 11 from one position to another through a considerable angular distance, in this instance a half-revolution, whilst also enabling the flame to be adjusted for neutrality, or for an oxidizing or carburizing composition, by slight turning movement at either of these positions, without appreciably disturbing the size of the flame.

This can be accomplished by drilling the ports 12 and 13 at double diagonals, that is to say the ports are displaced angularly in relation to each other about the axis as in the preceding form and also at reverse inclinations lengthwise of the plug. This in-

volves forming the oxygen and acetylene passages 3 and 4 in the body 9 in such manner that these passages are closer together at one side of the cock and farther apart at the opposite side, that is to say the passages approaching the cock are offset from the passages leaving the cock. With this arrangement, when the cock is in the position of Fig. 1 the largest areas are opened and the flame is accordingly of a larger size, whilst when the plug is in the position of Fig. 2 the areas of both the oxygen and the acetylene passes are cut down approximately half, resulting in a smaller flame. At either of these positions slight turning of the plug varies the areas of opening of the oxygen and acetylene passages in relation to each other, in order to adjust the percentage composition of the flame.

What I claim as new is:

In an oxyacetylene torch, a flame adjustment device consisting of a duplex plug cock having ports for oxygen and acetylene, respectively, said ports being angularly displaced with reference to each other about the axis of the plug and also at reverse inclinations lengthwise of the plug, the approach and departure passages in the stationary part of the cock being offset with relation to each other, so that by turning the plug from one position to another the areas of opening are changed from large to small or vice-versa whilst by slight turning of the plug at either position the ratio is variable.

JOHN J. CROWE.
